UNITED STATES PATENT OFFICE.

SAMUEL DAVID BLOCKER, OF COLUMBUS, OHIO, ASSIGNOR OF ONE-HALF TO
WILLIAM J. GREENE, OF COLUMBUS, OHIO.

NON-REFILLABLE BOTTLE.

SPECIFICATION forming part of Letters Patent No. 707,199, dated August 19, 1902.

Application filed November 11, 1901. Serial No. 81,872. (No model.)

To all whom it may concern:

Be it known that I, SAMUEL DAVID BLOCKER, a citizen of the United States, and a resident of Columbus, in the county of Franklin 5 and State of Ohio, have invented new and useful Improvements in Non-Refillable Bottles, of which the following is a full, clear, and exact description.

This invention relates to a bottle equipped 10 with certain novel devices for preventing the introduction of liquids into the bottle after its original contents have been decanted.

This specification is a specific description of one form of my invention, while the claims 15 are definitions of its actual scope.

Reference is to be had to the accompanying drawings, forming a part of this specification, in which similar characters of reference indicate corresponding parts in all the figures.

20 Figure 1 is a vertical section of the invention. Fig. 2 is a sectional view of the same, showing the bottle turned downward; and Fig. 3 is a section on the line 3 3 of Fig. 1.

The bottle may be constructed of glass or 25 any other material and has its neck *a* formed with an annular indentation *a'*, receiving a bead *b'* on the sleeve *b*, which is thus fitted rigidly on the neck *a*. The sleeve *b* extends inward over the top of the neck *a* and thence 30 upward to form a spout *b*². Within the neck is arranged a cup *c*, secured rigidly in place through the medium of an outwardly-projected flange *c'*, lying over the top of the neck *a* and under the inwardly-projected part of 35 the sleeve *b*, to which the flange *c'* is fastened by indentations on the sleeve engaged in openings in said flange. The cup *c* has an opening or valve-seat *c*² in its bottom communicating with the interior of the bottle,

40 and at its upper portion the cup has a contraction *c*³ internally threaded to form a holder. In this holder *c*³ is received a threaded tube *d*, which has an annular flange *d*² at its lower end to limit its upward movement 45 and which also has one or more openings *d*². When the tube *d* is screwed down, as in Fig. 1, the openings *d*² lie opposite the holder *c*³ and are thereby closed; but when the tube *d* is screwed up, as in Fig. 2, the openings are 50 free for the passage of liquid through the tube and out thereof by way of the openings men-

tioned. The tube *d* carries rigidly at its top a cap *e*, which fits over the spout *b*² and when the tube is moved downward bears on the inwardly-bent part of the sleeve *b* at the top of 55 the neck *a*. Within the cap *e* is carried a gasket *e'*, of cork or other material, arranged (see Fig. 1) to bear down on the top of the spout *b*² and hermetically seal the same. Now it may be seen that by applying one's 60 finger to the cap *e* and screwing the tube *d* up or down the spout *b*², and therefore the bottle, may be unsealed or sealed, as desired. This manual operation is quite distinct from 65 the non-refillable valve devices which act automatically, as will hereinafter appear.

f indicates a plug which is fitted slidably yet snugly within the tube *d* and is sustained by a spring *f'*, so as to normally cover and seal the openings *d*².

70 *g*, *g'*, and *g*² indicate three balls or weights of non-buoyant material, these balls lying in the cup *c*, and the ball *g* lying in the orifice *c*², to act as a gravity-valve therefor, the ball *g* lying on top of the ball *g'* and the ball *g*² 75 lying on top of the ball *g'* and being of such diameter that it may enter the tube *d* (see Fig. 2) to actuate the plug *f*.

When the bottle contains liquid but it is 80 not desired at that time to decant it, the cap *e* and the tube *d* should be screwed down. (See Fig. 1.) When the bottle is in active use, these parts may be left raised. (See Fig. 2.) When the bottle is in an upright position, the balls *g*, *g'*, and *g*² drop to their 85 lower position, the ball *g* sealing the opening *c*² and the balls *g'* and *g*² lying on top of the ball *g*. The plug, if actuated by the spring *f'*, lies over the openings *d*², keeping them 90 closed. Now it is clear that liquid cannot be forced into the bottle, nor can liquid be entered into the bottle by laying it on its side under the surface of a body of liquid, for the reason that the plug *f* will still be held over the openings *d*², and the ball *g*² will 95 be unable to roll from the side wall of the cup *c* up into the tube and against the plug *f*. When the bottle is turned vertically, or nearly so, with the neck downward, the weight of the balls *g*, *g'*, and *g*² will be placed 100 on the plug *f*, and this will overcome the spring *f'*, thus moving the plug to uncover

the openings d^2 . The liquid will now be free to run out; but it cannot be forced up through the neck, because of the volume of air in the bottle, which air cannot escape to make room 5 for the entering liquid.

Various changes in the form and details of my invention may be resorted to at will without departing from the spirit thereof. Hence I consider myself entitled to all such forms 10 as may lie within the intent of my claims.

Having thus described my invention, I claim as new and desire to secure by Letters Patent—

1. The combination with a bottle, of a 15 holder in the neck thereof, a tube provided with a closed upper end and an intermediate opening, said tube being adjustably fitted in the holder and the holder being capable of inclosing said opening, and a cap fastened to 20 the upper end of the tube and inclosing the major part of the tube, said cap extending downward and being movable with the tube into and out of engagement with the upper end of the neck of the bottle.

25 2. The combination with a bottle, of a holder in the neck thereof, and a tube with a closed upper end and an intermediate opening, said tube being adjustably fitted in the holder and the holder being capable of closing the said opening, a spout projecting upward from the neck of the bottle and surrounding the tube, and a cap fastened to the tube and inclosing the spout, for the purpose specified.

35 3. The combination with a bottle, of a cup set into the neck thereof and having a contraction at its upper end forming a holder, the cup also having an opening in its bottom, a tube set in the holder, said tube being 40 closed at its upper end and having an opening intermediate its ends, a spring-sustained means in the tube for commanding the liquid

flow through the opening, and a weight in the cup, said weight normally closing the opening in the bottom of the cup and being 45 capable of rolling into the tube to actuate the said spring-sustained means therein.

4. The combination with a bottle, of a holder in the neck thereof, a tube having a closed upper end and an opening intermediate 50 its ends, said tube being adjustably fitted in the holder and the holder being capable of closing said opening, a spring-actuated valve in the tube, and a weight arranged below the valve and capable of entering the 55 tube to open the valve.

5. The combination with a bottle, of a holder in the neck thereof, and a tube with a closed upper end and an intermediate opening, said tube being adjustably fitted in the 60 holder and the holder being capable of closing the said opening, a spout projecting outward from the neck of the bottle and surrounding the tube, a cap fastened to the tube and inclosing the spout, for the purpose specified, 65 a valve arranged in the tube, and a weight located below the valve and capable of entering the tube to open the valve.

6. The combination with a bottle, of a cup set into the neck thereof and having a contraction at its upper part forming a holder, the cup also having an opening in its bottom, a tube located adjustably in the holder, the tube having a closed upper end and an intermediate opening, a valve arranged in the 70 tube, and a weight carried in the cup and capable of entering the tube to open the valve.

In testimony whereof I have signed my name to this specification in the presence of two subscribing witnesses.

SAMUEL DAVID BLOCKER.
